CRATE FOR RECTANGULAR-SECTIONED ARTICLES

James C. Nichols, Chicago, Ill.

Application May 18, 1934, Serial No. 726,201

3 Claims. (Cl. 217—5)

This invention relates to improvements in shipping cases and refers specifically to a shipping case for electric refrigerators or the like provided with means whereby the refrigerator or other device to be shipped is maintained in a rigid position within the case.

The utility, objects and advantages of my invention will be apparent from the accompanying drawing and following detail description.

In the drawing, Fig. 1 is a perspective view, illustrating my packing or shipping case as assembled, parts being broken away.

Fig. 2 is a plan sectional view taken on line 2—2 of Fig. 1.

Referring in detail to the drawing, 1 indicates generally a packing or shipping case for a rectangular prism-shaped body indicated diagrammatically at 2, such as, for instance, an electric refrigerator or other article which in itself is relatively heavy and may be possessed of a delicate finish which must be protected. The case 1 may comprise opposite sides 3, 3 and 4, 4, top 5 and bottom 6, assembled in prismatic form and housing the refrigerator 2.

The walls of each of the sides 4 may be constructed of plywood mounted upon longitudinal frame members 7, cross-frame members 8 and reinforcing member 9. The wall of the bottom 6 may also be constructed of plywood mounted upon cross frame members 10, which protrude a relatively short distance beyond the wall at each end. Two cleats 11 may be mounted upon the opposite side of the bottom plywood wall and may be coextensive with the edge of the wall, said cleats 11 being disposed transversely to members 10. Cleats 11, as will be hereinafter more fully described, serve as supports for the legs or base of the refrigerator 20. The wall of top 5 may be constructed of plywood and may be mounted upon the rectangular frame 12.

The walls of sides 3 may also be constructed of plywood and as a feature of my invention the longitudinal frame members 13 upon which said walls may be mounted may each comprise cleats 14 and 15, which may be coextensive with the length of the walls, cleats 14 being wider than cleats 15 to provide a right-angle corner 16 at each frame member 13. Packing material 17 may be suitably secured in each corner 16, said material being relatively soft and resilient, and being coextensive with the length of the members 13. Transverse frame members 18 may be positioned at each end of the wall and may be secured to the same side of the wall which carries members 13. If desired, a transverse reinforcing member 19

may span the wall of each of the sides 3 intermediate their length, said reinforcing member being equal in thickness to, and flush with, cleat 14. The reinforcing members 19 may carry padding or packing material 20 similar in character to the padding 17.

When utilizing my invention, sides 3 and 4 and top and bottom 5 and 6 respectively are preformed and previous to assembly padding 17 and 20 is tacked or otherwise secured respectively to members 13 and 19. The refrigerator 2 or other article to be crated is then mounted upon the bottom 6, the members 11 being adapted to support the legs or base of the refrigerator. Sides 3 are then secured at their lower ends to the bottom 6 and at their upper ends to top 5. In so securing sides 3, the corners of the refrigerator register with angles 16 and the refrigerator is held rigid by the confining cleats 14 and 15. The presence of the padding 17 in the corners 16, of course, prevents marring of the refrigerator finish while permitting the cleats to bear tightly upon the corners. Sides 4 are then positioned over the open ends of the parallelopiped formed by sides 3, top 5 and bottom 6 thereby completely enclosing the refrigerator within the crate.

It is to be noted that members 7, 8 and 9 serve as frame members for the plywood walls of sides 4 and when assembled said members are positioned exteriorly of the crate. However, members 13 when the crate is assembled, are positioned interiorly of the crate whereby to confine and hold the refrigerator 2 rigid. In addition to performing this function, members 13 serve as frame members for the support of the plywood walls 35 of sides 3.

The entire crate 1, of course, is preferably constructed of wood and the various constituent elements thereof may be nailed or screwed together both in preforming the sides, top and bottom, and in assembly.

I claim as my invention:

1. A crate for refrigerators or the like which comprises in combination, a top, a bottom and opposite sides joined in the form of a parallelopiped, characterized in that the walls of said confining members comprise relatively thin plywood panels and are supported by frame members and the frame members, of two opposite sides are positioned interiorly of the crate and serve to maintain the refrigerator rigid within the crate.

2. A crate for a rectangular-sectioned refrigerator or the like which comprises in combination, a top, a bottom and opposite sides joined together in the form of a parallelopiped, each of the sides 65

- comprising walls supported on frame members, said walls comprising relatively thin plywood panels, opposite sides being characterized in that the frame members therefore are mounted on the interior of the walls, and opposite frame members of said walls each comprise a pair of cleats secured together, one of said cleats being wider than the other to form a right-angle shoulder only the wider of said cleats being directly secured to said opposite sides, said shoulders being adapted to engage the corners of the refrigerator to maintain the same rigid within the crate.
3. A crate for a rectangular-sectioned refrigerator or the like which comprises in combination, a bottom and opposite sides joined together in the form of a parallelopiped, each of the sides com-
- 5
- 10
- 15

prising walls supported on frame members, said walls being constructed of relatively thin plywood, opposite sides being characterized in that the frame members therefore are mounted on the interior of the walls, and opposite frame members of said walls each comprise a pair of cleats secured together, one of said cleats being wider than the other to form a right-angle shoulder, the corners of said refrigerator registering with said right-angle shoulders, and padding carried by said members interposed between said shoulders and refrigerator corners, the remaining opposite sides being characterized in that the frame members therefor are mounted on the exterior of the walls.
